H. F. BLACKBURN ET AL.
OIL DISCHARGE JET.
FILED SEPT. 2, 1921.

Inventor

HENRY F. BLACKBURN
AND
EARL L. McMILLEN

By A. D. Jackson Attorney

UNITED STATES PATENT OFFICE.

HENRY F. BLACKBURN, OF BRECKENRIDGE, AND EARL L. McMILLEN, OF RANGER, TEXAS.

OIL-DISCHARGE JET.

Application filed September 2, 1921. Serial No. 498,117.

To all whom it may concern:

Be it known that we, HENRY F. BLACKBURN, a citizen of the United States, residing at Breckenridge, in the county of Stephens and State of Texas, and EARL L. McMILLEN, a citizen of the United States, residing at Ranger, in the county of Eastland and State of Texas, have invented certain new and useful Improvements in Oil-Discharge Jets, of which the following is a specification.

Our invention relates to gas jets for lifting oil out of wells by natural gas; and the object is to provide a simple jet which will be self acting to lift oil out of wells by utilizing the pressure of natural gas and another object is to make the gas engage the oil in a direction approximating the direction of the oil which is being discharged so that the flow of oil will not be impeded but pushed upwardly and saving the force of the momentum of the oil. Other objects and advantages will be fully explained in the following description and the invention will be more particularly pointed out in the claim.

Reference is had to the accompanying drawings which form a part of this application.

Fig. 1 is a side elevation of the jet, showing how a sleeve and a discharge pipe are connected to the lower end of the jet. Fig. 2 is a vertical section of the jet. Fig. 3 is a plan view of the jet. Fig. 4 is a bottom plan view of the same.

Similar characters of reference are used to indicate the same parts throughout the several views.

The jet is interposed between two sections of a discharge pipe. The jet has a body 9 and is threaded interiorly at the upper end 1 to receive the lower end of a discharge pipe section 10. The lower end is threaded at 2 for receiving the upper end of a discharge pipe section 3. The section 3 may be forty feet more or less and has perforations 12 near the lower end for admission of oil from the oil producing sands. The jet has an opening 8 therethrough to form a passage for oil from the section below to the section

above. The oil flows up through the discharge pipe and the jet 9. In order to aid and increase the flow of oil and to make the oil flow, provision is made for utilizing the pressure of natural gas to force the oil upwardly. A sleeve 6 is screwed on the lower end of the jet 9 and extended down any suitable distance to form an annular chamber 7 about the pipe section 3 for collecting and concentrating the gas pressure. The gas is let into the oil passage through ducts 5 in the jet 9 at a small angle to the direction of the flow of oil so that the gas will be going as nearly as possible in the direction of the oil flow so that the gas will not interrupt but aid the flow of oil.

In operation, the oil flows up pipe 3 and through the opening 8. The natural gas rises up in the annular space about the pipe 3 within the sleeve 6 and then escapes through the ducts 5 into the oil passage and so lifts the oil on through the discharge pipe.

This method is preferable to the methods of introducing air or steam or gas down into the wells for ejecting oil because in this method, the lift is always upwardly and none of the gas presses downwardly whereas steam or air or gas forced down into a well tends to force the oil back into the producing sands. The efficiency of the jet herein described has been fully demonstrated thoroughly in actual service.

The jet is threaded exteriorly at 4 for convenience in removing the jet in case the socket 1 should become plugged so that a spear cannot enter the socket for removal. The socket 1 is threaded interiorly to receive the pipe section 10.

What we claim, is,—

A jet for lifting oil from wells by natural gas through a discharge pipe consisting of a body member consisting of a single casting having an unobstructed passage for oil therethrough and adapted to be connected to sections of a discharge pipe above and below said body and having the lower end thereof cylindrically enlarged and having relatively long inclined gas ducts from the lower end

through said enlarged portion and terminating in said oil passage for directing gas approximately in the same direction as the passing oil and a sleeve surrounding a portion of the oil discharge pipe below said body and screwed on the lower end of said body for forming an annular chamber

about the oil discharge pipe for projecting gas through said ducts.

In testimony whereof, we set our hands 10 this 18th day of August, 1921.

HENRY F. BLACKBURN.
EARL L. MCMILLEN.
